HIS ATTORNEY.

UNITED STATES PATENT OFFICE

CHARLES W. SIMMONS, OF EASTON, PENNSYLVANIA, ASSIGNOR TO INGERSOLL-RAND COMPANY, OF JERSEY CITY, NEW JERSEY, A CORPORATION OF NEW JERSEY

CONTROL MECHANISM FOR PRESSURE-FLUID-SUPPLY LINES

Application filed November 12, 1927. Serial No. 232,801.

This invention relates to displacement pumps, but more particularly to a system in which the refilling period of the well tank is preferably regulated by a timing receiver forming an accumulator.

The objects of the invention are to simplify and cheapen the manufacture of the pump, obtain certainty and precision in action, and economy in operation.

10 Other objects are to enable the main control valve to be controlled by a main change valve, and the timing receiver to be controlled by an auxiliary change valve, both of which valves are simple in construction, 15 cheap to manufacture, and do not readily get out of order.

The main change valve is preferably controlled by an auxiliary control valve of any suitable or standard construction and the 20 other change valve may be controlled by the main line pressure for simplicity of operation. The auxiliary control valve is preferably responsive to the pressure in the timing receiver, which constitutes a simple and convenient mode of operation.

25 The entire controlling apparatus may be assembled in small space, so that it is compact, and there are no complicated parts requiring special attention.

30 I do not confine myself to the special number of elements enumerated as the functions of several elements may be combined in one element in a single valve casing, without departing from the spirit of my invention.

35 The invention is shown in one of its preferred forms in the accompanying drawing which is a diagrammatic representation of a displacement pump, partly broken away and partly in vertical section.

40 Referring to the drawings, the well tank A is adapted to be located in the well B which may be provided with the casing C. The tank has the usual high pressure fluid supply pipe D and the discharge pipe E leading to the

45 gas trap F, in case natural gas is used as the pressure motive fluid. The foot piece of the discharge pipe is preferably provided with the hole G for aeration purposes on the principle of the air lift. The gas trap F has a

50 vent pipe H to which other vent pipes of the

system may be connected. In case compressed air is used as the pressure fluid medium, this vent will lead to atmosphere, but in the case of gas, the vent may lead to a region or tank of lower pressure than the main supply.

55 A receiver J forms a source of high pressure fluid supply and another receiver K forms a low pressure timing accumulator, in which the gas or air is permitted to accumulate under low pressure and up to a predetermined maximum pressure for a time sufficient to allow the well tank A to be refilled with oil or liquid to be pumped.

60 An auxiliary control valve X preferably constructed like the "pressure controlled valve" shown in United States Patent No. 1,138,278 granted May 4, 1915, to Castle and Rogers is connected to the timing receiver by the pipe 17 fitted into the adjustable plug 14 at one end of the auxiliary valve chest 10.

65 A spring cup 28 at the other end of the chest 10 is connected by pipe 30 to the pipe 31 which connects with the vent H. The reference characters above used for the valve X

70 are the same as those used for similar parts in the said Castle and Rogers patent and the valve operates to admit maximum timing receiver pressure through pipe 8 to the plunger L of the main change valve O to actuate said

75 plunger and cause the main control valve P to open. When the timing receiver pressure again falls a certain amount below that required to operate the auxiliary control valve X, then the auxiliary valve returns to its original

80 position, allowing the cylinder Q of the change valve plunger L to exhaust back through pipe 8 and pipe 30 to the vent pipe 31 and gas trap vent H.

85 The well tank A is provided with a well exhaust valve R in the casing S connected by pipe 32 to the vent pipe 31. The exhaust valve R is moved to closed position when the main pressure fluid is supplied to the well tank A from the main receiver J through

90 pipe 33, main valve P and pipe 34 connected to the well pipe D. The holes 35 in the exhaust valve throttle the live pressure and cause pressure to be built up to close the valve against the spring 36. Upon reduction of pressure in the well tank A after dis-

charge, the exhaust valve is opened by the spring 36.

The main control valve P has a cup *a* tightly but slidably fitting the hollow plug *b* which is connected by pipe *c* to the casing of the main change valve O. A ball valve *d* controls the pipe *c* and vent pipe *e*, so that when the ball *d* is in the up position shown in the drawing, the back of the main control valve P is relieved of pressure and the main valve opens and remains open under the influence of the spring *f* until the well tank is discharged. The drop in pressure in the well and in the valve casing T causes a rush of pressure fluid over the collar *g* of the main valve P and through the restricted opening between said collar and the valve casing which blows the valve shut. The valve neck *h* is of slightly smaller diameter than the inside of the valve cup *a* forming opposed differential pressure areas with the larger area inside the cup and when pressure is restored inside the valve cup, the valve will close and remain closed until pressure is again relieved inside the cup.

The auxiliary change valve U is similar to the main change valve O, but controls the supply and exhaust of low pressure fluid to and from the timing receiver K. The high pressure pipe *j* leads from the main receiver pipe 33 to the casing of the change valve O as shown, and a branch pipe *k* leads from pipe *j* to the casing of the auxiliary change valve U. A reducing valve V of any suitable type is located in the pipe *k* and also a needle valve *o* forming a timing receiver control valve to regulate the time required to bring the timing receiver or accumulator up to maximum pressure. A pipe *p* connects the change valve U with the timing receiver K and a ball valve *q* controls the low pressure pipes *k* and *p* and the vent pipe *r*. A high pressure pipe *s* connects the cylinder *t* of the auxiliary change valve plunger *u* with the main well pipe 34 so that during discharge of the well tank A, high pressure fluid is supplied beneath the plunger *u* and the ball valve *q* is raised from its seat, which vents the timing receiver K through pipes *p* and *r* to the vent pipe 31.

Assuming that the parts are in the positions indicated in the drawing, in blowing position, the main control valve P is open, and the exhaust valve R is closed. The ball valves *d* and *q* of the change valves O and U are in raised position, which indicates that the cup or back of the main valve P is vented and the timing receiver K is vented and losing its pressure.

When the well tank A is discharged, the main control valve P automatically closes due to the sudden rush of pressure fluid around the collar or flange *g* and the drop in pressure in the timing receiver K has caused the auxiliary control valve X to return to

its initial position which vents the pipe 8 leading from the plunger L of the main change valve O through pipe 30 to pipe 31. The plunger L moves down and ball valve *d* changes position which restores pressure inside the cup *a* of main valve P and holds the valve shut.

The drop in pressure in pipe *s* leading to the plunger *u* of auxiliary change valve U causes said plunger to move downward, and the consequent change of position of ball valve *q* permits pressure to build up in the timing receiver K through pipes *k* and *p*. The time interval required for the building up of pressure in the timing receiver is sufficient for the refilling of the well tank A, and when maximum pressure is reached in the timing receiver K, the auxiliary control valve X again operates, pressure is restored underneath plunger L of the main change valve O, which relieves the pressure inside the main valve cup *a*, and the main valve opens. The restoration of pressure beneath plunger *u* of the auxiliary change valve U again vents the timing receiver, and the cycle is repeated as the tank A is discharged and refilled.

I claim:

1. A control mechanism for pressure fluid supply lines, comprising a main control valve located in the supply line, an exhaust valve controlled by the main pressure fluid supply, a timing receiver adapted to receive fluid from the main pressure fluid supply, and main and auxiliary change valves controlling respectively the main valve and the timing receiver, said main change valve being operable by pressure in the timing receiver to open the main valve.

2. A control mechanism for pressure fluid supply lines, comprising a main control valve located in the supply line, an exhaust valve controlled by the main pressure fluid supply, a timing receiver adapted to receive fluid from the main pressure fluid supply, main and auxiliary change valves controlling respectively the main valve and the timing receiver, said main change valve being operable by pressure in the timing receiver to open the main valve, and an auxiliary control valve interposed between the timing receiver and the main change valve and adapted to control the supply to said main change valve.

3. A control mechanism for pressure fluid supply lines, comprising a main control valve located in the supply line, an exhaust valve controlled by the main pressure fluid supply, a timing receiver adapted to receive a low pressure fluid from the main pressure fluid supply, main and auxiliary change valves controlling respectively the main valve and the timing receiver, said main change valve being operable by pressure in the timing receiver to open the main valve, and an auxil-

iary control valve interposed between the timing receiver and the main change valve to control the supply and exhaust pressure fluid to and from the main change valve.

5 4. A control mechanism for pressure fluid supply lines, comprising a main control valve located in the supply line, an exhaust valve controlled by the main pressure fluid supply, a timing receiver adapted to receive fluid from the main pressure fluid supply, main and auxiliary change valves controlling respectively the main valve and the timing receiver, said main change valve being operable by pressure in the timing receiver to open the
10 main valve, and an auxiliary control valve interposed between the timing receiver and the main change valve and adapted to control the supply to said main change valve, said auxiliary control valve being responsive to
15 the pressure in the timing receiver.
20

5. A control mechanism for pressure fluid supply lines, comprising a main control valve located in the supply line, a timing receiver adapted to receive fluid from the main pressure fluid supply, a main change valve operable by pressure in the timing receiver to open the main control valve, an auxiliary control valve interposed between the timing receiver and the main change valve and
25 adapted to open at a predetermined receiver pressure to admit pressure fluid to the main change valve, an auxiliary change valve controlling the supply and exhaust of pressure fluid to and from the timing receiver, and
30 means interposed between the supply line and the auxiliary control valve to establish a predetermined time interval for building up pressure in the timing receiver to open the auxiliary control valve.
35

40 In testimony whereof I have signed this specification.

CHARLES W. SIMMONS.
